UNITED STATES PATENT OFFICE.

SEYMOUR FIELD, OF QUINCY, MASSACHUSETTS, ASSIGNOR TO THE POWER EYELETTING MACHINE COMPANY, OF BOSTON, MASSACHUSETTS.

EYELETTING-MACHINE.

SPECIFICATION forming part of Letters Patent No. 603,023, dated April 26, 1898.

Application filed July 27, 1896. Serial No. 600,673. (No model.)

To all whom it may concern:

Be it known that I, SEYMOUR FIELD, of Quincy, in the county of Norfolk and State of Massachusetts, have invented certain new and useful Improvements in Eyeletting-Machines, of which the following is a specification.

This invention has relation to eyeletting-machines of the class typified by patent to F. W. 10 Merrick, No. 427,340, granted May 6, 1890, in which patent is illustrated a machine provided with devices under the control of the operator for moving the punch and its bed away from the point where the eyelets are 15 inserted to increase the space between the holes and means for arresting the feeding of the eyelets and causing the holes not supplied with eyelets to be made at a greater distance apart than usual for the reception of lacing 20 studs or hooks.

The object of the present invention is to provide a machine of the type referred to with adjusting means for increasing or decreasing the distances or spaces between the holes for 25 the eyelets and the greater distances or spaces for the studs; or, in other words, the object is to provide means for varying the position of the punch relatively to the lower set when it operates to punch a hole and for varying the 30 limits of the path of movement of the upper set, whereby the holes for the eyelets, as well as those for the studs, may be formed nearer or farther away from each other.

Another object of the invention is to provide 35 the machine with means under the control of the operator for effecting the increase or decrease of the space between the holes without loosening any screws and by merely shifting a lever to one side or the other, to equip the 40 machine with devices, also under the control of the operator, for withdrawing the raceway from the eyelet sets when holes are being punched for the studs or hooks, and to automatically shift the adjusting devices after 45 the wider-spaced holes for the studs have been made to cause the formation of the shorter-spaced holes for the eyelets.

It is the object of the invention, likewise, to provide a machine with additional improvements whereby it will be rendered highly ef-

ficient in operation, easier of adjustment, and simpler in construction.

To these ends, therefore, the invention consists in a machine having those features of construction and arrangement which I shall 55 now proceed to set forth in detail, and then point out in the claims which are appended hereto.

Reference is to be had to the accompanying drawings, forming a part of this specification, 60 and to the letters of reference marked thereon, the same reference characters indicating the same or similar parts or features, as the case may be, wherever they occur.

Of the drawings, Figure 1 represents in side 65 elevation an eyeletting-machine embodying my invention. Fig. 2 is an elevation from the other side of the machine. Fig. 3 is a plan view of the machine. Fig. 4 is a plan view of the top-set lever and the punch-bar, together with the mechanism for adjusting the 70 throw of the same to change the spaces between the holes in the upper. Fig. 5 shows in detail and partially in section a portion of the adjusting mechanism. Fig. 6 is a section 75 on the line xx of Fig. 3. Figs. 7 and 8 illustrate the cam-sleeve which is employed in adjusting some of the parts. Fig. 9 illustrates the eccentric-shaft and the parts mounted thereon for moving the raceway back from the 80 eyelet-sets. Fig. 10 shows the connection between the top-set lever and the yoke at the top of the movable bar hereinafter described in detail. Fig. 11 shows in detail the adjusting means for a portion of the machine, being a section on line 11 11 of Fig. 3.

In the drawings, a represents the supporting-frame of the machine, having a vertical bearing b , in which is journaled a stud c , provided at its upper end with a head d , in which 90 is pivoted at the top-set lever f . To one end of the lever f is secured the top set g , the other end h of said lever projecting through a wide yoke i in the upper end of a vertically-movable bar j , mounted in bearings at the end of 95 the frame. The cross-aperture in the yoke i is considerably wider than the end h of the set-lever, so that the said lever may oscillate on the stud c relatively thereto.

k is the power-shaft, which is suitably jour-

- naled in bearings l in the frame a , being provided on its end with a loose belt-pulley m , adapted to be connected therewith by a clutch n . On the shaft k is rigidly secured a disk o , having a cam-groove to receive a roller p on the end of the vertically-movable stud or bar j . When the shaft k is rotated, the bar j will be reciprocated vertically, as will be well understood. The end h of the top-set lever is provided with a spherical knob q , and between said knob and the upper and lower walls of the yoke I place cups r or sliding pieces having concave faces to receive the knob q . The yoke is arranged at a tangent to the path of oscillation of the lever f , so that when the lever is reciprocated the ball or knob q will move perfectly in its cup-like sockets or bearings r irrespective of the position of the set-lever relatively to the yoke.
- On a bracket s , extending out from a collar h' on the stud c , I bolt the punch-block bar t , which has at its front end a punch-block or abutment u . The bar t is stationary vertically and is provided at its rear end with upwardly-extending ears v , in which is pivoted the punch bar or lever w , the bar t being also provided with guides x for the front end of said lever. The front end of the lever w is provided with a socket to receive the punch y , suitably held therein by a set-screw z . In the rear of the punch y the lever w is formed, with a through-aperture a' to receive a block b' , having its end connected to the forked arms c' of a reciprocating bar d' , the latter moving in a bearing e' and being actuated by a disk f' , having a cam-groove into which a roller g' on the end of the bar d' extends. The cam-grooved disk f' is suitably secured to the driving-shaft k by a pin or otherwise.
- The top-set lever coacts with a vertically-reciprocated lower-set bar i' , which latter is guided in bearings j' on the frame and is actuated by a cam k' . The lower set l' is suitably mounted in its bearings and held therein by a screw m' .
- I so connect the punch bar or lever and the top-set lever that they are moved in unison about the stud c , providing devices whereby the distance to be traversed by them will be varied in accordance with the distance to be left between the holes formed by the punch, and also devices for adjusting the punch-bar lever and the top-set lever relatively to each other.
- It is of course understood that in operation the punch-bar is actuated to punch a hole in the upper and is moved back out of the way to permit the top-set lever to be moved down to enter the hole cut by the punch and to move laterally, so as to feed the whole upper laterally until the top set is in line with the lower set, when they are actuated to set an eyelet in the hole. Hence when it is desired to leave a greater space between two holes in an upper the punch must form a hole at a greater distance from the lower set, and therefore the upper-set lever must traverse a

greater distance in feeding the upper to the lower set, and it is also necessary that at the end of the movement of the upper set it should be exactly in alinement with the lower set, which latter is stationary, in order that they may coact properly in setting the eyelet. In addition to these devices I also provide a mechanism for limiting the path of oscillation of the top-set lever and the punch-bar and for varying it to suit the particular occasion, all as I shall now explain.

In a bearing m^{10} , bolted to the side of the frame, I mount a vertical rock-shaft n' , having on its lower end an arm o' , with a roller p' lying in a cam-groove q' in the disk o , so that when the disk o is rotated the shaft n' will be rocked or oscillated. The upper end of the shaft n' is provided with an arm r' , extending at right angles to the arm o' and connected by a link s' with a slideway t' , pivoted on the vertically-reciprocating rod j . The head d of the stud c is extended out in two bars v' , to form upwardly-extending ears 90 or guides u' for the top-set lever f , and below the bars is a slide w' , which has a portion x' , extending down into the slot y' in the slideway t' . z' is a small plate secured to the portion x' of the slide and extending under the 95 slideway, so as to hold the slide in place. Now it will be seen that when the rock-shaft n' is rocked it will, through the arm r' and the link s' , oscillate the slideway t' , and through the medium of the slide w' oscillate the top-set lever f on the stud c . Arranged beneath the bars v' , extending out from the head d , is a plate a^2 , having a curved slot b^2 , which is eccentric to the stud c and at an angle to the top-set lever f , and extending down into 100 said slot b^2 is a pin c^2 , secured to the end of the punch-block bar t . The slide w' is connected by a link d^2 with a lever e^2 , pivoted on the vertical shaft j . The plate a^2 has a rectangular portion f^2 , extending up between the 105 bars v' , so as to slide therein, and is apertured at g^2 to receive a pin h^2 , projecting up from the slide w' . Thus it will be seen that the abutment block-bar and the punch-lever are connected with the top-set lever, so as to 110 move therewith. When the lever e^2 is rocked around the shaft j to the left, (see Fig. 3,) it will, through the link d^2 , force the slide w' away from the shaft j , carrying with it the plate a^2 , so that the walls of the slot b^2 will 115 force the pin c^2 away from the top-set lever f , causing the abutment block-bar and the punch-lever to be swung around the stud c relatively to the top-set lever. This will increase the distance to be traversed by the 120 top-set lever as well as that traversed by the punch-bar.

The path of oscillation of the slideway t' being uniform, it will be readily seen that by moving the slide w' away from the center of 125 oscillation the slide will traverse a relatively greater distance and will therefore cause the top-set lever to be moved a greater distance, and by drawing the slide w' toward the pivot

of the slideway the said slide w' will traverse a relatively shorter distance, and thereby cause the top-set lever to traverse a shorter distance.

5 The lower set is stationary laterally, and the top set operates to feed the upper to the lower set after the hole has been punched in, as has been described. Hence when a greater distance between the holes is desired it is 10 necessary to punch a hole farther away from the lower set, and therefore the top-set lever must traverse a greater distance in feeding the upper along to the lower set, the punch bar or lever also traveling a relatively greater 15 distance. If the top-set lever and the punch-bar were made to travel a greater distance or move in a longer arc without varying the positions of the same relatively to each other, it would follow that the upper set would not 20 properly engage in the hole made by the punch, or, in other words, the rearward limit of movement of the top set would not be in alinement with the forward limit of movement of the punch; and hence, when it is necessary to effect a longer throw of the top set, 25 it is also necessary to adjust the punch-bar relatively to the top set, so that, when the punching action takes place, it will be exactly the point at which the top set descends to engage the hole. This adjustment of the punch-bar relatively to the top-set lever is effected 30 by the pin c^2 , traveling in the slot b^2 in the plate a^2 , the slot being at an angle to the set-lever, so that when the slide and the plate a^2 35 are moved forward to increase the arc of travel of the set-lever the punch-bar and the abutment-bar are swung slightly around the stud c , so as to cause the punch-bar to make a hole in the upper in that line to which the 40 top set and the lever f will be moved. The end of the path of movement of the top set in its forward direction is in alinement with the axes of the stud c and the shaft j , the cam-slot q' being so curved as to effect this, 45 the lower set being in that line and being stationary. Hence when the lever e^2 is thrust to the right in Fig. 3 it draws, through the medium of the link d^2 , the slide w' and the plate a^2 toward the shaft j . This movement 50 causes the top set g to move slightly laterally or forward toward the lower set, and the pin c^2 , sliding in the slot b^2 in the plate a^2 , will move the punch y nearer to the set g , as will be clearly seen. Thus the movement of the 55 lever e^2 automatically increases or diminishes the path of movement of the set-lever and adjusts the punch-bar relatively to the said lever.

By referring to Fig. 5 it will be seen that I 60 have provided lever e^2 with a sliding dog f^2 , having its front end serrated to engage the serrations g^2 on a sector-shaped plate h^2 . The dog or latch f^2 slides on suitable guides and is provided with a recess i^2 , having inclined 65 end walls j^2 k^2 . l^2 is a thumb-lever pivoted on the under side of the hand-lever e^2 and having its pivot m^2 cut away to form a semi-

cylindrical cam, which, when it is rocked, will have its periphery in engagement with the inclined walls j^2 or k^2 , respectively. When 70 it is desired to slide back the latch f^2 from the serrations g^2 , the thumb-lever l^2 is pressed toward the lever e^2 and the cam-like pivot m^2 engages the end wall j^2 of the recess and draws the latch back, so that the lever e^2 can be 75 moved to the right or to the left.

On the sector-plate h^2 I place an adjustable gage to limit the movement of the lever e^2 . The gage is conventionally illustrated as consisting of two pins o^2 p^2 , adapted to be inserted in any of a series of holes q^2 in the said sector-like plate. By means of these pins the amount of adjustment of the top-set bar and the punch may be limited. In order to adjust the setting and punching mechanism relatively to the cam q' , I place in the aperture in the link s' an eccentric sleeve s^2 to receive the pivot-pin r^2 , which connects the link s' with the arm r' . By adjusting the position of the cam-sleeve the link s' and the 90 arm r' may be adjusted relatively to each other.

In addition to causing the formation of holes at a greater distance apart than those first made by the punch for the reception of the eyelets it is desired to prevent the eyelets from being fed to those first-mentioned holes, since it is desired to place in them studs or hooks. Hence I shall now describe the raceway for the eyelets and the mechanism for preventing the eyelets from being fed to the said holes.

v^2 is the raceway through which the eyelets pass from the hopper w^2 and the receptacle x^2 . The raceway and the hopper and receptacle may be of any approved pattern, since I do not limit myself to the employment of any particular kind. The support y^2 for the raceway is pivoted at z^2 to a plate a^3 , the latter being itself pivoted upon a shaft b^3 , supported by the frame a of the machine and extending through to the other side of the same. The plate a^3 has an arm c^3 extending downward and provided with an inwardly-projecting roller lying in the cam-groove d^3 115 in a cam-disk e^3 . f^3 is a link pivoted to the support y^2 for the raceway and pivoted to the frame a . When the cam-disk e^3 is revolved, the pin in the cam-groove d^3 will cause the oscillation of the plate a^3 about the shaft b^3 120 and a consequent reciprocation of the raceway toward and from the set, as will be clearly seen. About the pivot g^3 for the link f^3 is placed an eccentric sleeve h^3 , which fits in the circular aperture i^3 in the link f^3 . By 125 turning the sleeve, which is formed with a polygonal flange j^3 for this purpose, the link f^3 may be adjusted vertically, so as to raise or lower the end of the raceway toward and form the work-plate k^3 , as will be understood. 130

In forming the holes for the reception of the eyelets after the hole is punched the top set enters into it and moves the work along into the path of the lower set, as has been

stated. As the lower set ascends it engages an eyelet in the end of the raceway, which has been moved forward, and the two sets firmly bind or secure the eyelet in place; but when the holes are formed in the upper for the reception of the studs or hooks, which holes are at a greater distance apart than those formed for the eyelets, I provide means for throwing the raceway back, so that when the lower set rises it will not engage an eyelet therein. The mechanism for accomplishing this is as follows: The shaft b^3 , upon which the plate a^3 is mounted, is provided with a crank, on which said plate a^3 is pivoted. The other end of the shaft is provided with a bell-crank lever having two arms l^3 and m^3 . The arm l^3 is connected with a treadle below the working bench (not shown) by a link n^3 . Hence when it is desired to move the raceway back from the lower set the treadle is depressed, rocking the shaft b^3 , and consequently dropping the plate a^3 and the support y^2 for the raceway v^2 , thus moving the end of the raceway out of the path of the lower set. At the same time I desire to automatically shift the lever e^2 forward, so as to increase the path of motion of the upper set, and hence I connect the arm m^3 of the bell-crank lever by a link o^3 with an inwardly-extended arm p^3 , forming a part of the thumb-lever l^2 . When the treadle is depressed, it draws upon the arm p^3 to turn the pivot m^3 and draw the latch back from engagement with the sector-plate, and finally swing the lever e^2 forward until it engages the pin o^2 . After the holes for the studs have been formed in the upper pressure upon the treadle is removed and a spring q^3 draws the arm l^3 of the bell-crank lever upward, and a spring r^3 , interposed between the lever e^2 and the sector-like plate h^2 , throws the lever e^2 backward into its original position.

Having thus explained the nature of my invention and described a way of constructing and using the same, although without attempting to set forth all the ways in which it may be made or all the modes of its use, I declare that what I claim is—

1. A machine for setting eyelets, comprising in its construction punching devices, a movable-set lever, a stationary set, means for moving the punching devices and the set-lever, for causing the work to be fed forward, means for changing the position of the set-lever and the punching devices relatively to the stationary set, to increase or decrease the path of movement of the said parts, and devices for simultaneously adjusting the last said means to vary the increased or decreased path of movement of the said parts.
2. A machine for setting eyelets, comprising in its construction punching devices, and a movable-set lever journaled on the same vertical axis; a stationary set; means for moving the punching devices and the set-lever in unison about their axis, to cause the work to be fed forward to the stationary set after it is punched; means for increasing or decreasing

the play of the said punching devices and set-lever; and a lever under the control of the operator for adjusting the last said means to vary the increased or decreased movement of the said movable parts.

3. In an eyeleting-machine, the combination with a movable-set lever, punching devices, a stationary set, means for moving said lever and punching devices in unison toward and from said stationary set, movable means for moving said punching devices and set-lever relatively to each other, and adjustable devices for simultaneously limiting the movement of the last said means.

4. In an eyeleting-machine, the combination with a movable-set lever, punching devices, and a stationary set, of means for moving said set-lever and said punching devices simultaneously toward and from the stationary set, movable means for moving said punching devices and said set-lever relatively to each other and to the stationary set, a lever for operating the last said means, and an adjustable gage for limiting the movements of the last said lever.

5. In an eyeleting-machine, the combination with an oscillating set-lever, oscillating punching devices, and a stationary set, of a rocking arm pivoted by a single pivot to said lever and to said punching devices, and means for moving said pivot toward and from the axis of the rocking arm, to vary the throw of said lever and devices.

6. In an eyeleting-machine, the combination with a set-lever, punching devices, a stud around which said lever and said punching devices oscillate, and a stationary set, of a slotted rocking arm, a pivot slidable in said slot to connect the arm to said lever and said punching devices and a lever for moving said pivot along said slot toward and from the axis of the rocking arm.

7. In an eyeleting-machine, the combination with a movable-set lever, and movable punching devices, of a rocking arm connected to the set-lever by a pivot, means for moving the pivot toward and from the axis of the rocking arm, and means for simultaneously moving the punching devices toward and from the movable-set lever.

8. In an eyeleting-machine, the combination with a movable-set lever, and movable punching devices both movable around the same axis, of a rocking arm having a slideway, a slide connected to said set-lever and said punching devices, and means for moving said slide along said slideway to increase or diminish the path of movement of said set-lever and said punching devices about said pivot.

9. In an eyeleting-machine, the combination with a movable-set lever, and movable punching devices, both oscillating about the same axis, of a rocking slideway, a slide pivoted to the set-lever, a lever on the axis of said slideway, and a link connecting the slide with the lever.

10. In an eyeleting-machine, the combination with a stud having a head, a set-lever pivoted in said head, punching devices movable around said stud, a rocking arm, a plate 5 movable along the head and pivoted to said rocking arm, a cam-and-pin connection between the said plate and said punching devices, and means for moving said pivot along the rocking arm, whereby the path of movement of the punching devices and the set-lever is varied, and the punching devices are moved relatively to the set-lever. 10
11. In an eyeleting-machine, the combination with a stud having a head, a set-lever 15 pivoted in said head, punching devices movable around said stud, a rocking arm, a plate movable along the head and pivoted to said rocking arm, means for moving said pivot along the rocking arm, whereby the path of movement of the punching devices and the set-lever is varied and the punching devices 20 are moved relatively to the set-lever, and a gage for limiting the movement of the last said means. 20
12. In an eyeleting-machine, the combination with a stud having an elongated head forming a guideway, a set-lever pivoted to said head, a movable plate slidable in said guideway and having a slot at an angle to the lever, a punch-lever and abutment-bar movable about said stud, said punch-lever and abutment-bar having a pin entering said slot in the movable plate, a rocking slideway, 30 a slide pivoted to the plate, and a lever for moving said slide in said slideway. 35
13. In an eyeleting-machine, the combination with a movable-set lever, punching devices, a stationary set, a rocking arm pivoted to said lever and punching devices, and means 40 for moving the pivot toward and from the axis of the rocking arm, of a lever under the control of the operator to actuate the said means for moving the pivot in one direction, and a spring to actuate the said means for 45 moving the pivot in the other direction. 45
14. In an eyeleting-machine, the combination with the movable-set lever, the movable punching devices, means for moving them simultaneously, means for varying the play 50 of the set-lever and the punching devices, and means connected therewith for adjusting the punching devices relatively to the set-lever, of a lever for operating the last two said means. 50
15. In an eyeleting-machine, the combination with the movable-set lever, the movable punching devices, means for moving them simultaneously, means for varying the play 55 of the set-lever and the punching devices, and means connected therewith for adjusting the punching devices relatively to the set-lever, of a lever for operating the last two said means, and a gage for limiting the play in either direction, of said lever. 60
16. In an eyeleting-machine, the combination with the laterally-movable set-lever and punch, a rock-shaft having an arm, and a link 65 connecting the arm with the said lever, of an eccentric-sleeve interposed between the link and the arm, whereby when the sleeve is turned the position of the link is changed relatively to the arm, or vice versa. 70
17. In an eyeleting-machine, the combination with a punch, a movable-set lever, a stationary-set lever, and means for varying the positions and play of the punch and set-lever 75 to form small-spaced holes or larger-spaced holes, of a raceway for eyelets, means for bodily moving the raceway longitudinally to withdraw it when the parts are in the positions to make holes with said larger spaces 80 between them, and a single lever for directly and positively operating the two said means simultaneously. 80
18. In an eyeleting-machine, the combination with two sets, of a raceway for delivering eyelets to said sets, a pivot for supporting the raceway upon the frame of the machine, a treadle, and means between said treadle and the pivot for adjusting the latter to move the raceway from the sets. 85
19. In an eyeleting-machine, the combination with the frame, a shaft, and a cam thereon, of two sets, a raceway for the eyelets, a lever in operative connection with the cam and connected with the raceway for reciprocating the raceway, a pivot for the raceway and means additional to the aforesaid parts for shifting said pivot to draw said raceway bodily away from said sets. 90
20. In an eyeleting-machine, the combination with the sets, a raceway, a lever to which the raceway is pivoted, an eccentric-pivot for the said lever, and means for turning said pivot to move the raceway from the sets. 100
21. In an eyeleting-machine, the combination with the sets, a raceway, a lever to which the raceway is pivoted, a link pivoted to the frame of the machine and to the raceway, an eccentric-pivot for said lever, and a cam operating the free end of the said lever, of means 105 under the control of the operator for rocking the eccentric-pivot. 105
22. In an eyeleting-machine, the combination with the sets, and a raceway pivoted upon the frame of the machine and movable toward 110 and from the sets, of a link also connecting the raceway with the frame, and means for adjusting the link relatively to the frame. 115
23. In an eyeleting-machine, the combination with the sets, and a raceway pivoted upon 120 the frame of the machine and movable toward and from the sets, of a link also connecting the raceway with the frame, and a pivoted eccentric interposed between the link and the frame to adjust the link vertically relatively 125 to the frame. 125
24. In an eyeleting-machine, the combination with a movable-set lever, a stationary set, and punching devices, of means for increasing or decreasing the play of the movable set 130 and the punching devices, a swinging lever for operating the said means, a sector-like

plate having serrations, and a dog mounted in guides on said lever and adapted to engage the serrations on the sector-like plate.

25. In an eyeleting-machine, the combination with a top-set lever, a rock-shaft having a rocking arm, a movable pivot connected to the said top-set lever, a hand-lever connected to the said pivot and movable about the said rock-shaft as a pivot, a stationary sector-like

10 plate, a movable dog in the hand-lever adapted

to engage the plate, and a thumb-lever mounted on said hand-lever for operating the dog.

In testimony whereof I have signed my name to this specification, in the presence of two subscribing witnesses, this 30th day of 15 June, A. D. 1896.

SEYMOUR FIELD.
